UNITED STATES PATENT OFFICE.

JOHN MANNING VAN HEUSEN, OF JAMAICA PLAIN, MASSACHUSETTS.

EYEGLASSES.

1,407,450.

Specification of Letters Patent. Patented Feb. 21, 1922.

Application filed February 16, 1921. Serial No. 445,344.

To all whom it may concern:

Be it known that I, JOHN MANNING VAN HEUSEN, a citizen of the United States, residing at 101 Robinwood Ave., Jamaica Plain, in the county of Suffolk, State of Massachusetts, have invented certain new and useful Improvements in Eyeglasses; and I do hereby declare the following to be a full, clear, and exact description of the invention, such as will enable others skilled in the art to which it appertains to make and use the same.

My invention is an improvement in eyeglasses, and relates to that type of glasses known as "pince-nez", that is the type wherein means engaging the nose is relied upon to hold the glasses in place.

Glasses of this type often lose their grip upon the nose, due chiefly to the fact that they have a tendency to slip toward the apex of the nose where the guards are incapable of exerting their proper gripping action. This slipping is due mainly to the spring action on the guards, the essentially wedge shape of the nose, and the similarly inclined engaging faces of the guards, all of which co-operate to impart to the guards and glasses, movement toward the apex of the nose, and this tendency is increased and facilitated by the lubricating qualities of the natural secretions of the skin.

Materials having a high coefficient of friction, as for instance cork, and materials whose engaging faces are roughened to provide increased frictional engagement, as for instance tortoise shell, have been used as liners for the guards to prevent the glasses from slipping off the nose, with but slight benefit. If such materials are non-elastic, as for instance roughened tortoise shell they do not cushion, and pain to the wearer results. If they are elastic and of a cushioning nature, the engaging surfaces of the liners quickly become coated with the natural lubricant of the skin secretions, which increases the tendency to slip, and facilitate such slipping.

One object of the present invention is to provide a liner, which while serving as a cushioning liner for the guard, will also resist the tendency of the guard to slip on the skin in a direction to dislodge the glasses.

Another object of the invention is to prevent the above mentioned creeping action

of the glasses so that they will not lose their grip on the nose.

Another object is to provide glasses of the "pince-nez" type which will firmly retain their grip on the nose. 60.

In the drawings;

Figure 1 is a back view of a pair of eyeglasses provided with the improved guard liners,

Figure 2 is a section on the line 2—2 of 65 Figure 1,

Figure 3 is a section on the line 3—3 of Figure 2,

Figure 4 is an enlarged diagrammatic section showing the arrangement of the pile. 70

Because of the shape of the nose, which is somewhat similar to a pyramid having its base downward and its apex upward, inclined surfaces are presented, which converge or incline toward each other toward 75 the apex and toward the junction of the said surfaces, that is upwardly and outwardly. Glasses of the "pince-nez" type do not tend to slip downward, since to slip downward the guards must be forced apart. 80 On the contrary the glasses tend to move upward and outward, that is toward the apex of the pyramid of the nose. In order to resist such upward and outward movement the guards should present an engaging surface with a high coefficient of friction so far 85 as regards movement in such direction. It is not necessary however that there be any large amount of frictional resistance toward movement inwardly and downwardly. 90 On the contrary in order that the glasses may hold to the best advantage, it is desirable that such frictional resistance to movement in such direction should be as nearly as possible eliminated. 95

With this object in view I provide a liner for the guards of fabric material, having a pile surface on its free face, and with the pile threads inclined in the same direction with respect to the plane of the guard. The 100 pile of the fabric should be relatively stiff, and for this purpose I have found a suitable material to be mohair.

In the present embodiment of the invention the improved liners are shown in connection with the guards 1 of a pair of eyeglasses, consisting of the guards, the lenses 2 and the nose piece 3. Each liner is composed of warp threads 4, weft threads 5 and pile threads 6. The pile threads are so 110

woven with respect to the warp and the weft, that when the fabric has been shaved in the usual manner of preparing pile fabrics, the pile of the fabric will be inclined 5 with respect to the plane of the fabric, and with all the threads of the pile inclined in the same direction. The liners which are of approximately the same size and shape as the guards, are arranged upon the engaging 10 faces thereof, in such manner that when the glasses are held in normal position, that is with the nose piece upward, and with the lenses in substantially a vertical plane, the pile threads will extend vertically. Since 15 the guards are inclined with respect to a plane through the lenses at an angle of about 45° the pile threads will be at an angle of approximately 45° with respect to the longitudinal axis of the guards. With 20 this arrangement, when the glasses are in place on the nose, the free ends of the pile threads will engage the skin and will resist any tendency of the glasses to move toward the apex of the nose. The peculiar arrangement 25 in fact tends to seat the glasses more firmly on the nose. While the guard is shown in connection with glasses having a resilient nose piece, which is relied upon to provide sufficient pressure to hold the 30 glasses in place, it will be understood that the improved guards are equally well adapted for use with guards of the "Sure-on" type, that is with that type of guard moved toward the face by a spring independent 35 from the nose piece.

The improved liners may be attached to the guards in any desired manner, as for in-

stance by gluing the liner directly to the guard. In the present embodiment of the invention the guard is provided with a peripheral groove, and the liner is enough larger than the guard to lap in this groove, either at its ends, or throughout its circumference. A clamping ring 7 encircles the guard at the groove, and clamps the liner 45 edge within the groove.

I claim.

1. In eyeglasses, a guard liner of pile fabric, the pile threads of the fabric being inclined in the same direction with respect 50 to the plane of the guard.

2. In eyeglasses, a guard liner of pile fabric, the pile threads of the fabric being inclined in the same direction with respect 55 to the plane of the guard, and in a direction substantially parallel with a plane through the lenses.

3. Eyeglasses having guards provided with liners of pile fabric, the pile threads of the fabric extending upwardly and outwardly to resist upward and outward movement of the guards on the nose. 60

4. Eyeglasses having guards provided with liners of pile fabric, the pile threads being inclined upwardly with respect to the 65 guards when the glasses are in place.

5. Eyeglasses having guards provided with liners of pile fabric presenting contact filaments inclined upwardly.

6. Eyeglasses having guards provided 70 with liners of pile fabric.

In testimony whereof I affix my signature.

JOHN MANNING VAN HEUSEN
